UNITED STATES PATENT OFFICE.

EDWIN RINGOLD, OF CINCINNATI, OHIO, ASSIGNOR TO NEUHAUS,
TROUNSTINE & CO., OF SAME PLACE.

DESIGN FOR A BADGE.

SPECIFICATION forming part of Design No. 29,118, dated August 2, 1898.

Application filed July 11, 1898. Serial No. 685,710. Term of patent 31 years.

To all whom it may concern:

Be it known that I, EDWIN RINGOLD, a citizen of the United States, residing at Cincinnati, in the county of Hamilton and State of Ohio, have invented and produced a new and original Design for a Badge, of which the following is a specification, reference being had to the accompanying drawing, forming part thereof.

The drawing is a plan view showing my new design for a badge or other similar article.

As shown in the drawing, the leading or material features of my design are a scroll center with flags on the right and left thereof, palms extending upward from the base of the scroll on each side behind the flags until they droop over the top of the scroll, a star at the base of scroll, and the whole surmounted by an eagle clutching in its talons implements of war. The scroll is suggestive of the war documents that contain the grimly laconic history of the armies out of which has grown

the Grand Army of the Republic. The star is emblematic of the Grand Army of the Republic. The flags suggest the original thirteen States and the palms are symbolic of rejoicing. The center of the scroll is left plain, so that any special occasion on which the badge is to be used may be impressed. The center of the star within the ring is also left plain, so that any local device, such as the seal of a city, may be impressed.

Having described my invention, what I claim as new, and desire to secure by Letters Patent, is—

The design for a badge or other similar article as herein shown and described.

In testimony whereof I have hereunto set my hand.

EDWIN RINGOLD.
